(57) **CLAIM**

The ornamental design for a space divider of a milking parlor, as shown and described.

DESCRIPTION

1. Space divider of a milking parlor
  2. Space divider of a milking parlor
- Fig. 1.1 is a front elevation view of a space divider of a milking parlor in accordance with our new design;
Fig. 1.2 is a right side elevation view thereof;
Fig. 1.3 is a top plan view thereof;
Fig. 1.4 is a left side elevation view thereof;
Fig. 1.5 is a right side perspective view thereof;
Fig. 1.6 is a left side perspective view thereof;
Fig. 2.1 is a front elevation view of the space divider of a milking parlor according to a second embodiment;
Fig. 2.2 is a right side elevation view thereof;
Fig. 2.3 is a top plan view thereof;
Fig. 2.4 is a left side elevation view thereof;
Fig. 2.5 is a right side perspective view thereof; and
Fig. 2.6 is a left side perspective view thereof.
